UNITED STATES PATENT OFFICE.

ANDREW McCALAIN, OF NASHVILLE, TENNESSEE.

REFRIGERATOR AND FILTER.

SPECIFICATION forming part of Letters Patent No. 314,597, dated March 31, 1885.

Application filed July 10, 1883. (No model.)

To all whom it may concern:

Be it known that I, ANDREW McCALAIN, a citizen of the United States, residing at Nashville, in the county of Davidson, in the State of Tennessee, have invented a new and useful Improvement in Refrigerators and Filters, of which the following is a specification, reference being had to the accompanying drawings, in which—

10 Figure 1 is a representation of a vertical section of the entire apparatus. Fig. 2 is a top view of the same with the lid removed. Fig. 3 is also a top view of the same with the lid and the water-receptacle both removed. Fig. 4 is a vertical section of the entire apparatus, taken on the line $\alpha\alpha$ of Fig. 1.

15 The object of the invention is the construction of a combined refrigerating and filtering apparatus having one filtering-chamber and a series of separate refrigerating-chambers independent of and having no communication with each other by means of doors or other openings, and so combined with said filtering-chamber and the other parts herein described that they will be kept at a cold temperature while the ice used is dissolving and long after the ice has dissolved, while the water used for refrigeration shall at the same time be filtered and pass off into a tank below to be drawn off for use.

20 The invention is designed as an improvement on the device shown in Patent No. 188,650, granted to me March 20, 1877; and it consists in the peculiar combinations and the construction and arrangement of parts, hereinafter more fully described, and then specifically pointed out in the claims.

25 In the accompanying drawings only two refrigerating-chambers are represented, but of course the number may be increased, if desired, by lengthening the filtering-chamber and the entire apparatus proportionately and introducing additional partition-walls, as hereinafter described.

30 Referring now to the details of the drawings, A represents a water-tank, which supports the entire superstructure B, which, through resting on the tank A, is not attached to it. The superstructure B consists of the refrigerating-chambers H and H', filtering-chamber k, tube m, tray n, and three water-compartments, 1 2 3, which so communicate

with each other as to form one general water-compartment, as follows—viz., the water-compartment 1, which also forms an ice-receptacle, situated immediately under the opening C', communicates below the water-compartment 2, which is under the filtering-chamber k, and communicates through the compartment 1 with the water-compartment 3, which is above the refrigerating-chambers.

Within the walls of superstructure B the water-receptacle C fits loosely, and rests on the top of the inner vertical wall, l, of the filtering-chamber k, and on the top of tray n, and on the stops P, fixed in the front corners of superstructure B, and is supplied with handles, by which it may be let down into said superstructure B and withdrawn at pleasure.

35 H H' represent the refrigerating-chambers formed on the bottom plate, B', of the superstructure B, and are independent of each other. The end walls, b, of superstructure B serve as the outer walls of chamber H and of the chamber k, situated at the other end of the row of refrigerating-chambers. Chamber H does not extend to chamber k, and thus leaves a space which forms the water-compartment 1 between the rear wall of chamber H and the inner wall of chamber k. The chambers H H' are provided each respectively with doors h h', cut in the front wall of the superstructure B.

40 The wall l, which serves as the inner wall of the chamber k and rear wall of chamber H', rises vertically from the bottom of superstructure B to a line which is level with the top of tray n, and extends from one end wall to the other end wall, and parallel with the rear wall, g. This wall has an opening, l', of rectangular shape, formed in its lower edge at the end opposite chamber H, to afford a communication between the water-compartments 1 and 2.

45 The rear and end walls of superstructure B serve as the outer and end walls of chamber k, respectively. The bottom of chamber k is perforated at one end, and placed at such a distance above the bottom of superstructure B as to leave a space, which forms the water-compartment 2.

50 A vertical tube, m, is firmly attached to the rear wall of the superstructure B, with its upper end attached to the bottom of the tray n, from whence it passes through the portion of chamber k opposite its perforated bot-

tom, with its lower end communicating with the water-compartment A when the super-structure B is placed thereon.

The tray n is situated at the upper corner 5 of the chamber k, with its bottom slightly higher than the top of the refrigerating-chambers H and H', and is formed with two vertical perforated walls, set at right angles to each other, and attached to the rear and end walls 10 of superstructure B.

The receptacle C is furnished with a sponge-box, D, attached to its bottom, and bordering on inner extremity of the opening C'. Said box is formed by two sides, D', of triangular 15 shape, with their bases attached to the bottom of receptacle C, the vertical edges of which are joined by parallel walls d d', perforated at their lower ends, the inclined edges being joined at their top by a plate, Q, which 20 covers only a portion of said edges, the remaining portion being covered by a perforated plate, Q', hinged to the bottom of chamber C, said perforated plate being locked in position by a slide, q, working in guides q' 25 on the plate Q. A slide, i, working between the walls d d', regulates the flow of water through the sponge-box D. Sponge or other filtering material being firmly compressed into the box D, the perforated lid is let down and 30 fastened by the slide q, which is slipped over its upper edge.

An opening, C', of rectangular shape, is formed in the bottom of receptacle C, and is provided with wall c'', rising vertically from 35 its edges to the top of the walls of the receptacle C. One of the walls of the receptacle C forms one of the end walls inclosing the opening C', the inner wall being formed by the perforated wall d' of the sponge-box.

40 The walls inclosing and surrounding the opening C' are provided with a top or lid, L, hinged to the upper edge of one of the side walls.

The receptacle C being placed in position, 45 the opening C' comes directly over the water-compartment 1. Through this opening ice is dropped into the water-compartment 1. The opening C' is made a little smaller than this water-compartment, so that ice dropped 50 through the opening C' may not strike the edges of chambers H and H'. Water being poured into receptacle C, percolates through the sponge or other filtering material in the box D, and is regulated in its flow there- 55 through by the slide i, closing or disclosing the apertures f and g in the walls d d', respectively. The water passes through the opening C' into the water-compartment 1 below. Chamber k being well packed with fine 60 gravel and charcoal or other suitable filtering material, the water, entering through the perforations k', rises and percolates through the filtering material in chamber k till it reaches the perforations in the ends of the tray n, 65 when it enters the same and passes down through tube m into the tank A below. The chamber k being firmly packed with filtering

material, the water rises faster in the general water-compartment than in chamber k; but the inner vertical wall, l, of chamber k being 70 higher than the level of the top of the tube m the water will be held in the general water-compartment till it has time to sink to the level of the top of the tube m. When it has sunk to the level of the top of the tube m, it 75 can sink no lower, and as the top of chambers H H' is lower than the level of the top of the tube m these chambers will remain submerged in ice-water. Suitable filtering material being used—such as gravel and charcoal—it will 80 assume the ice-water temperature, and will retain that temperature and part with it more slowly than the water could do without its presence and contact. The walls of superstructure B are surrounded with double cas- 85 ing, with space between the casings, into which paper, charcoal, or other non-conductor of heat is to be placed. The walls of superstructure B being thus surrounded and its top closed with the lid O, and the chambers H H' 90 and the chamber k and the water-compart- ments being all situated below the water-re- 95 ceptacle C, the water in said receptacle C is first brought to an ice-water temperature, and the slide i is then elevated, so as to admit a gentle flow into the water-compartments below. The ice in the compartments below will dissolve slowly, and the chambers H H' and 100 their contents will retain a cold temperature while the ice below is dissolving, and long 105 after it has dissolved.

The water in superstructure B may be entirely removed and the chamber k drained, when it is desired to do so, by placing a piece of hose over the edge of one of the walls of superstructure B and extending it down 110 through opening C', to the bottom, and ex- tending it on the outside down to a point which is lower than the bottom of super- structure B, thus forming a siphon.

What I claim as new is—

1. The combination, with a series of refrigerating-chambers, as H H', an ice-receiver, as 1, water-compartment, as 3, and a filter, as k, of the water-receptacle C, extending over the 115 refrigerating-compartments, the ice-receiver, the water-compartment, and the filtering-chamber, substantially as described.

2. The combination, with a series of submerged refrigerating-chambers, as H H', and 120 a filtering-chamber, of an ice-receiver partially surrounded by said refrigerating and filtering chambers, substantially as described.

3. A combined refrigerator and filter con- 125 sisting of a series of refrigerating-chambers, as H H', filter k, and ice-receiver 1, in combination with a water-receptacle, as C, located over said parts and provided with an opening, C', coincident with the ice-receiver 1, as and for the purposes set forth.

4. In combination with a series of refrigerating-chambers, as H H', ice receiver 1, and filter k, a water-receptacle, as C, located over 130 said parts and provided with an opening, C',

coincident with said receiver, said opening being inclosed or surrounded on three of its sides by vertical walls, and on the fourth by a filtering-box, as D, substantially as and for the purposes specified.

5. The combination, with a series of refrigerating-chambers, as H H', and an ice-receiver, as 1, of a water-receptacle arranged above the ice-receiver and refrigerating-chambers, and 10 provided with a passage through it of smaller diameter than the ice-receiver, substantially as and for the purpose specified.

6. The combination, in a combined refrigerator and filter, of a series of refrigerating-chambers and a water-compartment with the 15 tray n and tube m, the upper end of the tube extending above the top of said chamber, and its lower end extending below the bottom of the same, substantially as shown, and for the purpose described.

ANDREW McCALAIN.
